Patented Dec. 12, 1967

209,537

SIGNAL LIGHT HOUSING

Charles L. Craddock, 4211 Burbank Blvd.,
Burbank, Calif. 91505

Filed Aug. 3, 1966, Ser. No. 3,325

Term of patent 14 years

(Cl. D48—24)

Fig. 1

Fig. 2

Fig. 3

Fig. 4

Fig. 5

Fig. 6

FIGURE 1 is a perspective view of a signal light housing showing my new design;

FIGURE 2 is a side elevational view;

FIGURE 3 is an end elevational view;

FIGURE 4 is a perspective view of a modified form of the housing shown in FIGURES 1-3;

FIGURE 5 is a side elevational view of the device shown in FIGURE 4; and

FIGURE 6 is an end elevational view of the device shown in FIGURE 4.

I claim:

The ornamental design for a signal light housing, substantially as shown and described.
